UNITED STATES PATENT OFFICE.

ERNEST N. OLSON AND SWAN SWANSON, OF MUSKEGON, MICHIGAN.

MOLDING-MACHINE.

1,383,748.

Specification of Letters Patent.

Patented July 5, 1921.

Application filed August 30, 1920. Serial No. 408,901.

To all whom it may concern:

Be it known that we, ERNEST N. OLSON and SWAN SWANSON, citizens of the United States, residing at Muskegon, in the county 5 of Muskegon and State of Michigan, have invented certain new and useful Improvements in Molding-Machines, of which the following is a specification.

This invention involves improvements in 10 a known type of molding machines wherein are used for purposes of general coöperation a rotary table adapted to be intermittently operated to bring successive mold boxes or molds into operating positions beneath a 15 vertically movable core presser, there being provisions for actuating said core presser to force a core into the mold. The operation of the presser is of course in timed relation to the operation of the rotary table, taking 20 place at a period when the table is stationary.

With the foregoing in view the present invention resides in improved operating means for the core presser, special actuating 25 means whereby the molds are elevated as they are moved from operating position to a position for lifting out from the rotary table for the removal of the molded article, together with other novel details of construction.

In the present instance the molding machine is designed primarily for the making of molded rubber battery jars and similar articles of manufacture.

35 In the accompanying drawings, Figure 1 is a vertical sectional view of the molding table embodying the essential features of the invention;

Fig. 2 is a top plan view of the same;

40 Fig. 3 is a vertical sectional view showing more particularly the mechanism for intermittently operating the rotary table and controlling the valves by which the passage of the pressure medium to the pressure cylinder is controlled:

Fig. 4 is a view on the line 4-4 of Fig. 3, more clearly showing the clutch devices and two of the valve operating members;

Fig. 5 is a perspective view of the spring 50 which coöperates with the clutch pin, and its offstanding operating projection;

Fig. 6 is a combined view showing in per-

spective the elements of the mold or mold box;

Fig. 7 is a sectional view showing the bottom portion of the pit and illustrating in an exaggerated manner the inclined surface which elevates the molds as they pass from operating position to a position for removal from the rotary table;

Fig. 8 is a sectional view of the clutch means showing more clearly the relation of the actuating projection on the bed with respect to the spring coöperating with the clutch pin, the view being about on the line 65 8-8 of Fig. 1.

Fig. 9 is a detail perspective view of a detachable auxiliary frame plate for the openings in the rotary table.

Describing the invention specifically, the 70 machine forming the preferred embodiment thereof comprises a stand A, the bed B of which supports at one side the rotary table C, and at the other side carries the operating mechanism generally shown at D by which 75 the table is actuated intermittently, and the valve mechanism similarly operated to control the depression of the cores as herein-after set forth. The table C operates about the axis 1 consisting of a central trunnion, 80 and suitable anti-friction bearings 2 are preferably used intermediate the bed B and the table C. The table C is equipped with a suitable number of mold or mold box receiving openings 3 seen best in Fig. 2, to 85 which the mold boxes 4 may be supplied by hand or otherwise, and similarly removed. The mold boxes 4 are seen best in Fig. 6, as comprising a removable side 5 formed with lugs 6 at its lower edge to enter openings 90 7 in the bottom of the mold box proper and establish an interlocking connection at this point. Likewise catches 8 at opposite ends of the mold box are adapted to engage projections 9 at opposite ends of the removable 95 side 5, in an evident manner. The mold box 4 has the sides and ends thereof formed with removable uppermost section 4^a of increased thickness, thereby establishing shoulders 4^b for the purpose of controlling 100 the height of the jars. Sections of different widths may be employed to obtain jars of different depths. Adjacent to shoulders 4^b the sides and ends of the box 4 have slots 4^c

therein. On the bottom of the mold box 4 are one or more cam projections 10 which taper from one end to the other. On the bottom of the mold box are mold ribs 4⁴ which coact in the molding operation to produce spaced supporting ribs on the bottom of the molded article.

The mold boxes are designed to be placed in the openings 3 of the rotary table C as 10 said table rotates progressively and intermittently, the said boxes being thereby carried into position beneath a vertically movable plunger or presser 11 disposed above the table C and the bed B to coact with a plug 15 or core 11' in the molding operation. In the bed B below the presser 11 is formed a pit 12 into which the mold box passes as the table C rotates, so as to assume its operative position beneath the presser. When each 20 mold box reaches its operating position beneath the presser the core which is previously dropped into the mold box upon the plastic material is caused to move downwardly into the same by the operation of the piston 12^a 25 in the cylinder 13 which is supported by a standard 14 extending upwardly from the bed of the stand A. The piston 12^a is connected by a piston rod 15 with the core presser 11 and fluid pressure pipes 16 and 17 lead to the portions of the cylinder 13 above and below respectively, the piston 12^a. The pipes 16 and 17 are in communication with a supply pipe 18 leading to a reservoir containing any suitable pressure medium 35 such as water, oil, air, or the like. At the union 19 which connects the pipes 16, 17 and 18 is a control valve of any suitable type operable by a valve lever 20 which in one 40 position causes communication between the pipe 18 and the pipe 16, and in another position establishes communication between the pipe 17 and the pipe 18, cutting off the communication between the pipes 16 and 18 and vice versa.

45 The means to operate the valve device including the lever 20 comprises a pair of pendant kicker bars or actuating members 21 and 22, arranged in proper relation to operating cams which comprise notched portions 23 provided in grooves 24 of a main valve operating member 25. The operating member 25 consists of a constantly driven approximately circular element mounted on a drive shaft 26 operated in any suitable 55 manner by a fixed pulley 27 adjacent to the loose pulley 28. The shaft 26 is driven constantly during the use of the machine and the notches 23 are located approximately 120 degrees apart in relation to the periphery 60 of the grooves 24 so that during each revolution of the member 25, the valve 29 previously referred to is opened once and closed once. This action of the valve results in a downward stroke of the presser 11 and an 65 upward stroke, lowering and raising the

same into and out of engagement respectively with the mold core.

The means to operate the table C is also actuated from the shaft 26, and from the operating member 25 in fact, so that the latter is common to the valve mechanism and to the table actuating contrivances. It will be seen from Fig. 3 that the operating member 25 is equipped with a sustaining hollow clutch member 30 in which is received loosely 70 the internal concentric clutch member 31 having two notches therein at diametrically opposite points and designated at 32 (see Fig. 4). On the clutch member 30 is a curved spring 33 engaged with a clutch pin 80 34 operating in a radial opening through the clutch member 32, said pin being normally pressed by the spring 33 to enter the notches 32 of the clutch member 31 whenever the pin 34 arrives opposite said notches. The 85 spring 33 has a sustaining lifting arm 35 adapted during the rotation of the parts 25 and 30 to engage a projection 36 on a suitable bracket 37 carried by the bed B, whereby the spring 33 is lifted at its free end away 90 from the member 30 thereby pulling out on the pin 34 to disengage the latter from the abrupt wall of the notch 32 with which it may be engaged, permitting the clutch member 30 to rotate a one-half revolution with 95 out turning the clutch member 31, until the next succeeding notch 32 is engaged by said clutch pin 34.

Bearing in mind the above construction of clutch devices, and that the clutch member 100 31 is provided with a sleeve 31^a on which is keyed or otherwise secured the gear 38, and that the gear 38 is in mesh with a gear ring 39 on the outside of the table C, it will be evident that the operating member 25, driven 105 by the shaft 26 is adapted to actuate the table C intermittently through the corresponding operation of the internal clutch member 31 and its associated gear 38.

Fig. 9 shows an auxiliary detachable flat 110 plate 40 adapted to fit in an opening 3 of the table C to provide a convenient means for assisting in supporting the mold box when such box is of a size smaller than the one suitable to fit into the opening 3 itself. There 115 will be times when the battery jars to be molded by this machine will be of smaller size than those suitable to be molded by the boxes 4 which fit the openings 3, the openings 3 to be of a size suitable for the 120 maximum sized battery jars or article to be molded. The flat plates 40 may be of different sizes for reduced sized mold boxes.

Summary of operation of machine.

We shall assume that operators are in attendance upon the machine and mold boxes 4 are being placed in the openings 3 in a proper manner preliminary to the molding operation, the rubber or plastic composition 130

introduced therein and the cores inserted thereupon and removed from the machine after such operation, to enable the displacement of the molded article after such removal. During the operation of the drive shaft 26 the clutch member 30 will automatically connect the gear 38 with the operating member 25, and impart to said gear a partial revolution sufficient to impart to the table C that amount of movement necessary to bring a freshly placed mold box 4 into the pit 12 beneath the presser 11. There has been previously placed in the mold box as stated a predetermined and sufficient quantity of the composition from which the molded article is to be made, in plastic state. The parts 30 and 31 having become automatically unclutched through actuation of the spring 33 by the projection 36 engaging the arm 25, the movement of the table C ceases and the core box 4 is accurately disposed beneath the presser 11. Just at this time the operating member 25 has turned sufficiently to open the valve 29 and cause communication between the pipes 16 and 18. This quickly forces the piston 12^a downward and likewise through the presser the mold core, and presses the plastic substance therein into the space between the walls and bottom of the core and the walls and bottom of the mold box. The shoulder formed at 1^b in the walls of the mold box limits the upward flowing of the substance which is shaped or molded by the pressure of the core in the box 4. After the downward movement of the core 11' into the box 4 is properly completed the cam 23 of one of the members 21 or 22 not previously operated, operates to reverse the movement of the valve 29 and establishes communication between the pipes 17 and 18, so that the pressure medium flowing therethrough into the cylinder 13 raises the piston 12^a and the presser 11. All this while the table C has been stationary, but when the presser 11 has been elevated again the parts 30 and 31 are clutched together and the table C is fed forward, that proportion of its movement necessary to bring a fresh mold box beneath the presser and thus permit of a repeating of the operation which has just been described.

It will be understood that the arrangement of the cams 23 and the notches 32 of the clutch part 31 may be arranged in any suitable manner to properly time the relative movements of the valve 29 and the table C, it being necessary of course that the table C be stationary when the valve is operated because of the downward and upward stroke of the presser 11. For the purpose of withdrawing the molded article from the mold box the side 5 is removed, and as the article is withdrawn the portions of the molded substance projecting into and through the slots 4^c will be shaved off, so to speak, by the

operation of withdrawal in respect to those portions at the ends of the box. The portions at the sides of the box may be cut off by any suitable means after removal of the molded article.

Having thus described our invention, what we claim as new and desire to secure by Letters Patent is:

1. In a molding machine, the combination with a stand, a rotary table mounted thereon, mold boxes carried by the table and adapted to be advanced thereby, a constantly rotated operating element, a sleeve member loose thereon and having a driving connection with the table, a clutch pin carried by the sleeve and adapted to engage the rotating part, yielding means tending to move the pin into operative position, trip means for automatically moving the pin into operative position at a predetermined time whereby the table is intermittently rotated, a presser mounted in co-operative relation to the mold boxes, and means for operating the presser in timed relation to the table. 70

2. In a molding machine, a movable table, mold boxes carried by the table and adapted to be advanced thereby, a constantly rotated driving element, means actuated by the drive element for intermittently advancing the table, a presser mounted in co-operative relation to the mold boxes, fluid pressure means for operating the presser, including a valve, a valve lever, and connector bars connected to the lever and riding upon the constantly rotating driving element, said driving element being formed with cams to engage the bars and operate the valve to actuate the presser in timed relation to the table. 90

3. In a molding machine, the combination with a stand, of a movable table, mold boxes carried by the table and adapted to be advanced thereby, a constantly rotated driving element, gearing for advancing the table, a clutch connection between the gearing and the driving element, means for automatically controlling the clutch connection to intermittently advance the table, a presser mounted in co-operative relation to the mold boxes, fluid pressure means for operating the presser including a valve, a valve lever, and a pair of actuating bars connected to the valve lever and riding upon the constantly rotating driving element, said driving element being formed with cams for actuating the bars to control the valve and operate the presser in timed relation to the movements of the table. 105

4. In a molding machine, a rotative table, a bed supporting the table for intermittent operation, mold boxes carried by the table, a core, a core presser movable into and out of engagement with the core of each mold box when the latter assumes a certain posi- 120 130

tion on the bed, fluid pressure means for operating the presser including a valve, a valve lever, pendant connector bars depending from the valve lever, an operating member comprising a body having spaced grooves to receive the ends of the connector bars, and cams formed at said grooves to engage and operate the connector bars, said operating member having a clutch member projecting therefrom, a second clutch member adjacent that first mentioned, a spring actuated clutch pin intermediate said clutch members to connect the same at predetermined intervals, automatic means coöperating to operate the clutch pin to disconnect the clutch members and gearing connecting the second clutch member with the table.

5 In a molding machine, a rotative table, a bed supporting the table for intermittent operation, mold boxes carried by the table, cores disposed in the boxes, a presser engageable with each core to press the latter into each mold box when the box assumes a cer-

tain position on the bed, fluid pressure means for operating the presser including a valve, a valve lever, pendant connector bars depending from the valve lever, an operating member comprising a body having spaced grooves to receive the ends of the connector bars, and cams formed at said grooves to engage and operate the connector bars, said operating member having a clutch member projecting therefrom, a second clutch member adjacent that first mentioned, a spring actuated clutch pin intermediate said clutch members to connect the same at predetermined intervals, automatic means coöperating to operate the clutch pin to disconnect the clutch members, and means for intermittently driving the table from said operating member.

10 In testimony whereof we affix our signatures.

ERNEST N. OLSON.
SWAN SWANSON.
